CLAIM

The ornamental design for a wire organizer, as shown and described.

DESCRIPTION

FIG. 1 is a front perspective view of the wire organizer showing my new design;

FIG. 2 is a front elevational view of the wire organizer thereof;

FIG. 3 is a rear elevational view of the wire organizer thereof;

FIG. 4 is a right elevational view of the wire organizer thereof;

FIG. 5 is a left elevational view of the wire organizer thereof;

FIG. 6 is a top plan view of the wire organizer thereof; and,

FIG. 7 is a bottom plan view of the wire organizer thereof.
